(57) **CLAIM**

The ornamental design for a vacuum bottle, as shown and described.

DESCRIPTION

FIG. 1 is a perspective view of a vacuum bottle showing the new design.

FIG. 2 is a front view thereof, the rear view being a mirror image of the front view.

FIG. 3 is a left side view thereof.

FIG. 4 is a right side view thereof.

FIG. 5 is a top view thereof.

FIG. 6 is a bottom view thereof; and,

FIG. 7 is a cross-sectional view taken along line 7—7 in FIG. 5.

The broken line showing is for illustrative purposes only and forms no part of the claimed design.
